UNITED STATES PATENT OFFICE.

JOHN WILLIAM FAESSLER, OF MOBERLY, MISSOURI.

FLUE-EXPANDER.

SPECIFICATION forming part of Letters Patent No. 739,160, dated September 15, 1903.

Application filed July 9, 1903. Serial No. 164,799. (No model.)

To all whom it may concern:

Be it known that I, JOHN WILLIAM FAESSLER, residing in Moberly, in the county of Randolph and State of Missouri, have invented 5 certain new and useful Improvements in Flue-Expanders, of which the following is a specification.

My invention is an improvement in the class of boiler-flue expanders in which a tapered 10 pin or mandrel is employed in connection with a series of surrounding rollers and a slotted box which incloses the latter and is adapted to be inserted in the end of the flue. The expansion is produced by driving the mandrel 15 in, whereby the rollers are forced out laterally and correspondingly through the slots of the box.

The main feature of the invention is the construction and combination of parts where- 20 by the expander is adapted for reversal, so as to operate effectively on flues projecting different lengths from the flue-sheet.

The details of construction and combination of parts are as hereinafter described, ref- 25 erence being had to the accompanying drawings, in which—

Figure 1 is in part a side view and in part a section of my improved flue-expander. Fig. 2 is a cross-section on the line 2-2 of Fig. 1. 30 Fig. 3 is a perspective view of the roller-box and an attachment thereof whereby it is held in the cylindrical body or collar of the tool. Fig. 4 is a perspective view of the body or collar. Fig. 5 is a side view of a pin employed for disconnecting the roller-box from the collar.

1 indicates the tapered mandrel proper, and 1^a the enlarged head thereof, which is pro- 35 vided with transverse holes for a rod for turn- ing it. The tapered portion of the mandrel 40 passes through the roller-box 2, having a se- ries of radially-longitudinal slots in which rollers 3 are arranged and adapted to move in and out, according as the mandrel is adjust- ed. The said box 2 is provided with an en- 45 larged circular head or collar 2^a.

4 indicates the cylindrical body or collar of the tool. The same is provided interiorly 45 with a circular rib 4^a, which is in turn pro- vided with a groove 4^b. It will be noticed 50 that this rib 4^a is located nearer one end of the body or collar 4 than the other. It is pre- 55 ferably located a distance from one end of

the collar 4 equal to the thickness of the head 2^a of the roller-box 4, so that when the parts are fitted together, as shown in Fig. 1, 55 the said head 2^a is flush with the adjusting end of the collar 4.

The means for detachably connecting the roller-box with the collar is a pin 5, (see Fig. 3,) the same consisting of an enlarged body 60 and a reduced portion formed on the outer end of the same. The body fits in a corre- 55 sponding radial socket or bore formed in the roller-box 2, and the reduced portion fits and is adapted to slide easily in the groove 4^b of 65 the collar 4.

The pin 5 is seated upon the coil-spring 6, which serves to hold it duly en- gaged with the groove in the rib 4^a, as shown 70 in Fig. 1. It will be seen that the pin per- mits the parts 2 and 4 to rotate freely upon 75 each other, but prevents their longitudinal movement. It is apparent that by depress- 80 ing the pin 5, so that its reduced end is clear of the groove 4^b in the collar 4, the box 2 may be slid out of and thus removed from the col- 85 lar 4. This is effected by inserting the pin— say such as shown in Fig. 5—in the radial hole 7, formed in the collar 4 and communicating with the groove 4^b thereof. It is obviously 90 necessary to adjust the roller-box 2 and collar 80 4 so that the pin will exactly coincide with the said hole 7, and for this purpose the ends of the collar 4 and the head 2^a of the roller- 95 box are provided with radial grooves or lines 9, Figs. 3 and 4, which when brought into 100 coincidence indicates the parts are in proper position for effecting detachment. The in- 105 sertion of the pin depresses the spring-pin 5 and enables the parts to be easily detached.

The object of this detachment will be better 105 understood from the following statement. Boiler-flues are sometimes cut off longer than necessary to be used before putting them into the boiler, and consequently when this is done they project too far outside of the flue-sheet, 95 and hence the operator is prevented from pro- 110 ceeding to roll and expand the flues in the boiler-heads. In other words, the projection of the flues from the heads prevents the ex- 115 pander from being inserted in the flue far enough to allow the rollers to be arranged in line with the inside flue of the sheet or, in other words, arranged at the proper point for ex- 120 pansion. It will be seen that when the body

or collar 4 is arranged as shown in Fig. 1 the roller-box 2, with its rollers 3, cannot be inserted in the flue to the same length as would be practicable if the collar 4 were reversed in 5 position, since it would then project a less distance over the box and rollers, owing to the fact that the grooved rib 4^a is located nearer the left-hand end of the collar than the other. By detaching the roller-box and reversing it and the collar 4 relative to each other the 10 described adjustment may be readily made. In such case it is apparent that the enlarged head 2^a of the roller-box will be in contact with the other side—to wit, the right-hand side— 15 of the rib 4^a. My improved flue-expander is thus adapted to be used with a collar at all times and yet to be applied and operate upon flues of different lengths. In other words, the collar being reversible and constructed 20 in the proportions indicated is adapted for use with flues cut one-half inch too long. When flues are more than one-half inch too long, the collar 4 may be entirely removed. When the roller-box has been detached from 25 the collar and the latter reversed, it is apparent that upon reversing the roller-box in the collar the spring-pin 5 will strike the rib 4^a and that it must be pushed back into its socket in order to allow it to slide under the 30 rib and into the groove thereof. For this purpose I provide the collar 4 with radial holes 7^a, (see Figs. 1 and 4,) which are located on opposite sides of the rib 4^a. A pin is inserted through either of these holes for de- 35 pressing the spring-pin 5, as will be readily understood, so that the spring-pin will pass under the rib as required.

The body or head 2^a of the roller-box 2 prevents dust and dirt from entering between 40 the collar and head, and thereby lengthens the life of the tool. Since the collar 4 always

extends over the rollers more or less, it prevents them from falling out of the box 2 when the expander is being handled outside of the flue, also when the expander is being 45 inserted in the flue.

As thus constructed the expander is composed of few parts and is very durable and efficient. The parts are made of tool or machine steel.

What I claim is—

1. In a flue-expander of the class specified, the combination, with the roller-box having a circular enlarged head, of the surrounding body or collar having an internal rib located 55 nearer one end of the collar than the other, the said collar having the same internal diameter on both sides of the rib, to adapt it to receive the head of the box at each end, and means for detachably connecting the 60 roller-box and collar, substantially as described.

2. The improved flue-expander comprising a tapered mandrel, a slotted roller-box having an enlarged circular head and a series of 65 longitudinal slots, rollers arranged in said slots and adapted to project therefrom, and a reversible body or collar surrounding the roller-box and having an internal rib which is grooved and located nearer one end of the 70 collar than the other, and a spring-supported pin held in the roller-box and engaging the groove of the collar, the collar being provided with a radial hole coinciding with the pin whereby provision is made for depressing the 75 latter as required to release the roller-box and allow reversal of the collar for the purpose specified.

JOHN WILLIAM FAESSLER.
